TIME SWITCH

Fritz E. Carlson and Johannes West, Chicago, Ill.

Application June 5, 1941, Serial No. 396,702

3 Claims. (Cl. 200—38)

Our invention relates to automatic time control systems and to time and labor saving device of this nature and more especially to clock or motor operated time switch mechanisms such as may be adapted for use in the control of various kinds of apparatus or machinery, including for instance intermittently operating machines, processing devices, furnaces, lighting and heating systems and the like.

Some of the objects of our invention are to provide a better and more dependable control device of the class described; to provide for a wider range of accurate pre-settings for various duties; to provide such a device or attachment comprising means adapted for setting to fix or predetermine definite general time periods both of non-operation and of intermittent operation, the latter according to some variable condition, such as temperature, etc.; and to provide clockwork or the like combined with energy storing and release means or motor adapted to apply positive force with quick release of energy sufficient to assure prompt and positive action of the appropriate control means according to specific needs.

An illustrative embodiment of this invention is shown by the accompanying drawing in which:

Figure 1 is substantially a front elevation of the control apparatus and mounting from which the detachable front casing or cover, not here shown, has been removed.

Fig. 2 is mainly a section on the line 2—2 of Fig. 1 and shows the time index dial at the left, with a conventional circuit diaphragm connected below.

Fig. 3 is a section taken on the line 3—3 of Fig. 2.

Fig. 4 is a somewhat angular section taken on the line 4—4 of Fig. 1, with the dial at the right.

Fig. 5 is a section taken at line 5—5 on Fig. 4, and shows, in front elevation, the rearmost pair of ratchet or star wheels with their respective actuating fingers and corresponding cams. (See upper right corner in Figs. 1, 2 and 3.)

More in detail, the rotary dial disc 1 pivoted on fixed shaft 1' is driven by a conventional clockwork mechanism, not shown, through a lateral shaft 2' and pinion 2 meshing with gear teeth 1" on the periphery of said disc 1. There are actually two switches S and S', front and rear, the latter comprising two spring arms 3 and 4, which are secured to a block of insulation 5' and connected in part by leads 6 and 7 to a source of current, for instance, battery B. The disposition of said arms 3 and 4 is controlled by a pair of ratchet or "star" wheels 8 and 9 respectively 55

which are rigidly connected together as a unit by a hub h on a common pivot stud 65 set on a frame back plate 5, in such manner that the points of the wheel 8 are staggered with respect to those of the companion wheel 9. The rear spring arm 3 has a lateral finger 10 which overlies and intermittently contacts the spring arm 4 or a similar finger thereon in the manner shown in Fig. 2; and the arms 3 and 4 are alternately lifted by the passing points of the wheels 8 and 9 as these wheels are rotated (by said clockwork) in the direction of the arrow 11 in such manner that when the arm 3 is raised, relative to arm 4, by a point of the wheel 8, the circuit will be broken; and when the arm 4 is raised by a point on the wheel 9 it will engage said finger 10 and close the circuit.

A pair of independently adjustable single toothed cams 12 and 13 operate on the respective wheels 8 and 9 through pallet springs p and p'. These springs are so formed hookwise at their free tips t and t' as to advance the wheel unit 8—9 about half a tooth space upon each rotation of each of the cams 12 and 13.

The cam 12 is carried by a shaft 14 which has an outer index arm 15 having an inwardly turned tip or points 16 that can be fitted into any one of the outer circular series of notches or holes 17 in the disc 1. Similarly, the cam 13 is carried by a hollow shaft or quill 18 connected to an index arm 19 provided with an inwardly turned tip or point 20 that meshes with a second or inner series of notches or holes 21 on the face of said dial disc 1. The holes 17 and 21 on the dial 1 are arranged and spaced at any desirable intervals or parts of a twenty-four hour period, preferably one set of twelve for day and another such set in series therewith for night, so that the arm 15 may be set to close the switch at any selected time and the arm 19 may similarly be set to open the switch at a selected time.

Referring now to the other switch S next to said dial 1 and comprising a set of two contact springs 43 and 45 mounted at their lower ends on said block 5', it is to be noted that this switch is substantially similar to switch S'; but is operated differently. Here the said springs 43 and 45 are lifted alternately, to close and open, by a pair of toothed wheels 30 and 31 in mutually adjustable rotary or angular position and with their teeth usually in staggered relation. One of these wheels 30 is fixed to said dial, and the other, 31, is set on a hollow shaft or sleeve 32 which turnably embraces shafts 14 and 18 and has a short index arm 36, turned inward at its

pointed tip to engage the arcuately arranged holes 31. Hence, this switch S in operation continues at regular intervals to close and open the circuit, as will be further described.

By way of further illustrating our invention and showing a particular use thereof, we refer to the relay circuit connections appearing in Fig. 2. Here the source of electric current, as for instance said battery B, has two wheel controlled switch circuits connected thereto, one controlled by wheels 30 and 31 and the other by wheels 8 and 9. The one of these, through switch S, delivers current from the positive side or terminal 36 of said source through lead 41 to terminal 42 of spring 43, thence by contact 44 to spring 45 and to terminal 46 of said spring 45 from which a conductor 47 extends to a contact 48 set in the block 5' under spring 4 where connection is made to spring 4 when that spring is released by its control wheel 9. Thence the circuit leads through spring 4 to its terminal 49 and thence through said conductor 7 to the coil 51 of relay 52 and on back by conductor 53 to the negative side 54 of said source B.

The other of those said switch circuits, the one through switch S', delivers current from said terminal 36 through lead 56, control element 57 (which may be a thermostat), lead 5 to terminal 59 of spring 3, through contact 10 to spring 4, thence through said spring 4, contact 49, wire 7, 30 relay coil 51, and conductor 53, to said negative side 54.

Whenever said relay 52 is energized, as by current in coil 51, a secondary circuit is closed leading from said source B through lead 56, 35 motor M and relay spring 58, and back to B through terminal 54. Said motor may be used to serve any appropriate function desired as for instance, to control the damper of a furnace, not shown, but as will be understood.

It is to be understood that some of the details set forth may be altered or omitted without departing from the spirit of our invention as defined by the following claims.

We claim:

1. An automatic control device comprising a frame, a pivotally mounted dial thereon, means to rotate said dial continuously at a constant speed, index arms pivotally mounted coaxially

with said dial and carried thereon each in adjustable rigid relation thereto, a plurality of electric switching means mounted on said frame, ratchet and cam actuators also coaxial with said dial, and concentric shaft means connecting said arms and respective ratchet and cam means respectively.

2. In a switching device of the class described a mounting frame, a shaft secured rotatably thereon, time controlled means to drive said shaft at a substantially uniform rate, a pair of relatively adjustable single hump cams mounted adjacently on said shaft, a pair of medially bent spring pawls each mounted fixedly at one end on 10 said frame in operating alignment with its corresponding cam for medial contact therewith, where the pawls are angularly bent, a compound wheel having corresponding ratchet elements disposed side by side in mutually offset ratchet-point relation in operative alignment with said pawls respectively for advancement of said wheel thereby, and a pair of mutually interfering switch springs resting at times on the corresponding ratchet points whereby the switch is alternately closed and opened according to the relative setting of said cams.

3. In a switching device of the class described a mounting frame, a shaft secured rotatably thereon, time controlled means to drive said shaft at a substantially uniform rate, a pair of relatively adjustable cams mounted adjacently on said shaft, a pair of spring pawls each mounted fixedly at one end to said frame in operating alignment with its corresponding one of cams for medial contact therewith, where the pawls are angularly bent, a compound wheel having many corresponding ratchet elements or humps disposed side by side in mutually offset ratchet-point relation in operative alignment with said pawls respectively for advancement thereby, and a pair of somewhat overlapping switch springs disposed side by side and resting at times on the corresponding ratchet points of said wheel whereby the switch is alternately closed and opened according to the relative setting of the two said cams.
